METHOD OF AND MEANS FOR PHOTOGRAPHICALLY COPYING CHECKS, DOCUMENTS, ETC.

Albert L. Adatte, Bound Brook, N. J., and John V. Lizars, New Rochelle, N. Y.

Original application November 15, 1938, Serial No. 240,466. Divided and this application June 28, 1939, Serial No. 281,596

8 Claims. (Cl. 271—53)

This is a division of our application Serial No. 240,466, entitled: "Method of and means for photographically copying checks, documents, etc.," filed November 15, 1938.

5 The invention relates to the photography and more particularly to photographic apparatus to record discreet documents, drawings, and such matter.

One object of the invention is to provide apparatus for intermittent operation which permits simultaneously recording both the obverse and reverse faces of sheets of variable length.

Another object of the invention resides in the provision of new and improved means to insure 10 alignment of the sheet being fed in such a manner as to effect maximum economy of film.

Yet another object of the invention is to provide a machine of the class described in which the sheet to be photographed will function to 15 initiate a cyclic operation of the machine.

A further object of the invention is to provide a document photographing apparatus in which all mechanical elements are normally at rest and the illuminating means deenergized; the 20 insertion of a sheet or document to be photographed functioning to set the machine in motion and to energize the illuminating means.

Still another object of the invention is the provision of manually adjustable means to control 25 the length or duration of a cycle of operations initiated by the insertion of the document to be photographed.

Another object of the invention resides in the provision of a plurality of circuit-making contacts arranged in series relationship between a 30 source of electrical energy and the mechanism of the machine in such manner that a document to be photographed must be caused to engage each of said plurality of contacts to initiate operation of the machine, thereby additionally securing alignment of the images of the document 35 on the film.

Other objects and advantages will be apparent in the following description of a preferred embodiment of the invention which has been selected for illustration in the accompanying drawings. It will be understood, however, that many changes in form, construction and arrangement 40 may be made by those skilled in the art without departing from the scope of the invention as expressed in the appended claims.

Referring now to the drawings:

Figure 1 is a fragmentary side elevation of a machine embodying a preferred form of the 45 invention.

Figure 2 is a plan view of the machine shown in Figure 1.

Figure 3 is an end elevational view of the machine shown in Figures 1 and 2.

Figure 4 is an enlarged elevation of the left 5 end of the machine as viewed in Figure 1.

Figure 5 is a plan view of the structure shown in Figure 4.

Figure 6 is an end elevation of part of the mechanism shown in Figures 4 and 5 and is taken 10 in the plane 6—6 of Figure 4.

Figure 7 is an end elevation taken in the plane 15 7—7 of Figure 4.

Figure 8 is an end elevation taken in the plane 8—8 of Figure 4.

Figure 9 is an end elevation taken in the plane 15 9—9 of Figure 4.

Figure 10 is a front elevation of the camera of the device and its related driving mechanism.

Figure 11 is a side elevation taken in the plane 20 11—11 of Figure 10 and likewise shows the camera and its driving mechanism.

Figure 12 is an enlarged plan view of the camera and related structures shown in Figures 10 and 11.

Figure 13 is a detailed view of one element of the driving connection between the feeding and camera recording elements of the apparatus.

Figure 14 is a diagram of the electric circuits.

In the drawings the apparatus is conveniently 30 housed in a cabinet consisting of side and end walls 10 and 11, depending legs 12 and a separable top 13, removal of which affords access to the mechanism of the machine for purposes of maintenance and repair.

The operative elements of the apparatus, as well as its camera and related driving mechanisms are supported on longitudinally extending angular frame members 14 and 15 which in turn are carried by the side walls of the cabinet and maintained in fixed relationship by cross-bars 16, a plurality of which are utilized between the ends of frame members 14 and 15.

Referring now particularly to the lefthand end of the machine as viewed in Figures 1 to 5 inclusive: The upper surface of the cabinet defines a feed table 17 from which documents to be photographed are fed into the machine, the documents subsequently being discharged in a removable hopper 18 (Fig. 3). Simultaneously 45 with the movement of the document through the machine, its obverse and reverse faces are photographed on a film carried in a camera 19 which is operated simultaneously with the driving of the document, the surfaces of which are re-

50 55 55

flected on the film in the camera 19 through similar angularly disposed mirrors 20 and 21.

Considering more particularly the feeding of the document from its position on the table 17 to its point of discharge in the hopper 18: As shown in Figures 8 and 9, a feed roller 25 whose peripheral surface is tangential with the surface of the feed table 17, is journaled in bearing walls 26 and 27 (Fig. 4) which in turn are rigidly supported in an upright position on cross pieces 16 by means of angular bars 28. A second feed roller 29, journaled on a movable axis above the feed roller 25, is adapted to be raised or lowered into engagement with the roller 25 to positively feed a document to the right as shown in Figure 9 so as to cause the latter to move between the mirrors 20 and 21. To this latter end the roller 29 is journaled adjacent its ends on generally similar arms 30 (Fig. 8) which in turn are carried by a shaft 31 rotatably supported in the bearing walls 26 and 27. The arms 30 are constrained to move in unison by means of a bail 32 rigidly attached to similar leftwardly extending lugs formed on the arms 30.

25 The feed roller 25 is drivingly connected to a short shaft 35 by a gear train including a gear 36 fixed adjacent the left end of the feed roller shaft as viewed in Figure 4 which meshes with a gear 37 fixed to the short shaft 35. Shaft 35 30 is journaled adjacent its ends in the bearing plate 26 and a bracket 38 which is supported in fixed spaced relationship from the bearing plate 26 by means such as shouldered studs 39.

To insure complete travel of the full length 35 of the document through the field of the reflecting mirrors 20 and 21, a second set of feed rollers are provided on that side of the plane of the mirrors opposite the side upon which rollers 25 and 29 are mounted. More specifically, a feed 40 roller 40 which may be similar in all respects to the roller 25 is supported on an axis coincident with the plane of the axis of roller 25 and its peripheral surface is preferably tangent with the plane of the table 17. Roller 40 is journaled in the bearing plates 26 and 27 and its supporting shaft is provided with a pinion 41 which meshes with the gear 37 on shaft 35 so as to cause roller 41 to rotate with and in the same direction as roller 25. Movable supported above 45 roller 40 is a co-acting feed roller 42 which for purposes of rendering the mechanism of the device readily accessible is carried upon similar arms 43 pivoted on an axis 44 in the bearing plates 26 and 27 respectively. The weight of 50 roller 42 is effective to provide a driving engagement between the latter and the positively driven roller 41 so that the leading edge of a document after passing through rollers 25 and 29 will be engaged by rollers 40 and 42, thus insuring completion of the passage of the document through 55 the plane of mirrors 20 and 21. As has already been indicated, the feed roller 42 may be moved to a disabled condition as shown by construction lines at 45 in Figure 8 to permit access to the 60 parts of the device.

Referring now to the optical features of the invention, the principal of which is fully disclosed in the co-pending United States application, Serial No. 139,113, entitled "Method of 70 photographically copying checks, documents, etc.," the mirrors 20 and 21 are preferably front surfaced plane strips which are carried in similar holders 47 which in turn are carried by generally triangularly shaped plates 48 and 49.

75 Plate 48 is rigidly connected to an upstanding

arm 50 of bearing plate 27 and plate 49 is secured at 52 to a tie piece 53 which extends between and is anchored to the bearing plates 26 and 27. As shown in Figure 9, the mirror supporting plates 48 and 49 lies in a common plane 5 normally disposed to the plane of the table 17 and the reflecting surfaces of the mirrors 20 and 21 define right angles with the plane of their respective supporting plates. The images of the face and reverse sides of a document are reflected 10 by the mirrors 20 and 21 respectively through a vertical slot 54 in a light trap plate 55 supported in spaced relationship to the right of bearing plate 27 by means of studs and thumb screws 56 and 57 respectively.

15 The vertical plane of the mirrors 20 and 21 as defined by construction line 22 in Figure 9 bisects the opening defined by the slot 54 in plate 55 and defines one axis of a lens system 23 of the camera 19.

20 The camera 19 as shown in Figures 10 and 11 is removably supported upon a shelf 58 defined by a horizontal plate which bridges similar upright members 59 carried by tie pieces 16 which extend between the main longitudinal frame 25 members 14 and 15. Alignment of the lens system of the camera with the axis 56 is effected by spaced pins 60 which project upwardly from the shelf 58 to snugly engage suitable bores formed in the lower surface of the camera housing. The lens system 23 as indicated in Figure 11 is removably mounted in an upright boss 61 fixed to the shelf 58 adjacent its lefthand edge. The upper end of boss 61 is formed with spaced bearing arms 62 which movably support the pivoted 35 end of a clamping bracket 63 which functions to retain the camera in operative position on the shelf 58. Bracket 63 is a generally L shaped contour and is shown particularly in Figure 11, its shorter leg being provided with a leaf spring 40 64, the lower end of which is turned at 65 to engage the under surface of shelf 58 when the clamp is in camera holding position. A leaf spring 66 secured intermediate its ends to the longer end of clamping bracket 63 functions to 45 yieldably hold the camera on the surface of the shelf.

50 A film (not shown) in the camera 19 is arranged to be advanced synchronously with the movement of a document through the field of the reflecting mirrors 20 and 21 by means including a short vertically disposed shaft 67 which is journaled to a subframe 68 which includes spaced bearing members 69 rigidly supported by depending standards 70 which in turn are carried by the shelf 58. Intermediate the bearing members 69 shaft 67 carries non-rotatably thereon a worm wheel 71 which is drivingly engaged by a worm 72 fixed to a shaft 73, the left end of which as shown in Figures 4 and 8 is fitted with a pinion 74 (Fig. 8) which engages the driving gear 31. Thus rotation of gear 31 functions to 55 synchronously actuate feed rollers 25-29, 40-42 and shaft 73 which through the medium of worm 72 and worm wheel 71 rotates the shaft 67. As has been indicated, the shaft 67 is effective to advance the film in camera 19 and although the mechanism of the camera 19 constitutes no part of the disclosure of the present invention, it is pertinent to note that the upper 60 end of shaft 67 defines a plane or surface driving gear which, when the camera is in operative position, engages a complementary gear to advance the film in the camera.

65 Referring now particularly to Figures 3, 4 and 75

8, the shaft 35 and hence the main driving gear 37 are arranged to be driven by means including an electric motor 75 conventionally suspended on the under surface of spaced tie pieces 16 which bridge the main longitudinal frame members 14 and 15 adjacent the lefthand end of the machine as viewed in Figures 1 and 4. Shaft 35 projects leftwardly from the bracket plate 38 to receive a pulley 76 which is driven from an armature 10 pulley 77 of the motor 75 through the medium of a belt 78. It will now be apparent that operation of the motor 75 will function to rotate driving gear 37 and hence the feed rollers 25-29, 40-42 and the shaft 13 and finally the mechanism of the camera 19.

Now coming to the means employed to automatically initiate a cyclic operation of the machine: In the normal or rest condition of the device, the feed roller 29 is elevated above the 20 plane of the feed table 17 so as not to impede insertion of a document. More particularly, the levers 30 which support feed roller 29 for movement above the axis 31 are provided with arms 30a which extend angularly downwardly between 25 the pivotal axis 31 to carry similar pins 30b which engage similar slots 80a in plates 80b which are rigid with the shaft 31. A tension spring 79 acting between a fixed point in the frame of the machine and the plate 78 tends to 30 rotate the latter in a clockwise direction as viewed in Figure 8 to cause the lower end of the slot to bear against the pin. A camming arm 80 (Fig. 7) fixed to the shaft 31 is formed with a camming house 81 which rides upon an 35 irregularly shaped cam 82 fixed to the shaft 35 so as to rotate therewith. As shown particularly in Figure 7, cam 82 is formed with a dwell surface 83 of such radius that the nose of camming lever 80 will not prevent roller 29 from engaging the peripheral surface of roller 25, but, if the 40 rotation of cam 82 continues in a counterclockwise direction, a node 84 formed thereon serves to elevate camming lever 80 thereby moving shaft 31 in a counterclockwise direction. This 45 counterclockwise movement of shaft 31 is communicated to plate 80b which is fixed thereto and, through pin 30b, the levers 30 are likewise moved in a counterclockwise direction to elevate roller 29 out of engagement with roller 25 thereby 50 destroying the feeding action of the latter. The arrival of cam 82 in its feed roller disabling position as shown in Figure 7 is availed of.

Referring now to Figure 14 in which the electrical circuits of the preferred embodiment of the invention are disclosed:

The driving motor 75 is connected to a source of electrical energy represented by the lead wires 91 and 92. A pair of similar normally open contacts 93 and 94 are connected in series between the lead wires 91 and 92 by conductors 95, 96 and 97. Interposed between the conductors 96 and 97 is a relay 98 comprising an armature 99 and a stationary field coil 100. It will be seen that field coil 100 is connected in series between conductors 96 and 97. Armature 99 is pivoted at 101 and includes a rigidly connected contact finger 102 which is arranged, upon actuation of the armature, to close a contact 103 which is connected to one terminal 70 of the driving motor 75 by conductors 104 and 105.

The second terminal of motor 75 is electrically connected to conductor 95 by a wire 106. It will now be apparent that a circuit may be established to the driving motor 75 from the lead

wires 91 and 92 by closing the series arranged contacts 93 and 94 so as to actuate the armature 99 thereby closing the contact 103 to establish a circuit from lead wire 91 through conductors 106, 105, 104, contact finger 102 and lead 5 wire 107 to conductor 97 and thence to lead wire 92.

It is necessary to illuminate the document as it traverses the plane of mirrors 20 and 21 and to this end upper and lower lamps 108 and 109 10 are connected in parallel with the above described circuits of the driving motor. As shown in Figure 14, lamp 108 is connected between the lead-in wire 91 and the conductor 105 by conductors 110 and 111 and the lamp 109 is connected between the same sides of the circuit by conductors 112 and 113. Thus, when a circuit to the motor 75 is established by the closing of contact fingers 93 and 94 and the resultant operation of relay 98, the lamps 108 and 20 15 109 will be simultaneously energized.

As shown in Figures 4, 8 and 9, the lamps 108 and 109 are supported above and below the plane of the feed table 17 and in close proximity to the left side of the mirror supporting plates 25 48 and 49 as viewed in Figure 9. The placement of the lamps is such that their light is cast upon the obverse and reverse faces of the document as it moves beyond the feed rollers 25 and 29 and the depth of the mirror supporting 30 plates 48 and 49 as identified by their respective edges 115 and 116 (Fig. 4) is such as will prevent direct rays from the lamps from impinging upon the mirrors. The contact fingers 93 and 94 of Figure 14 are shown more particularly in Figures 4 and 9. They constitute spaced conductors 117 and 118 provided adjacent the upper ends of their respective vertical portions with contact points 119. The lower ends of the fingers 117 and 118 are turned laterally and secured to opposite faces of insulating arms 119 fixed to the oscillatory shaft 31. Preferably the finger 117 is somewhat more flexible than the finger 118 so that the former may be made sensitive to the impact of the leading edge of a document being fed into the machine. As shown in Figure 4, the feed rollers 25 and 29 are formed with spaced, aligned, peripheral 40 grooves 120 and the fingers 93 and 94 are positioned to operate in spaced pairs of these 45 peripheral grooves so that the leading edge of a document being fed into the machine will necessarily have to be aligned in order to simultaneously contact both fingers.

As has been pointed out heretofore, the feed 50 roller 29 is elevated out of engagement with the roller 25 when the machine is in its stationary or rest position, the condition being effected by lever arm 80 which is actuated by cam 82 to rock shaft 31 and through the lost motion connection 30b-80a and arms 30 to raise the roller 29 out of engagement with roller 25. As shown particularly in Figure 9, the arms 119 upon which the contact fingers 93 and 94 are supported will function to raise the latter into 55 the plane of the feed table 17 momentarily prior to the action of the aforementioned lost motion connection to disable the feed roller 29. Thus, in the rest position of the mechanism, the contact fingers 93 and 94 will occupy the relative 60 65 positions shown in Figure 9, that is, their resilient fingers 117 will be interposed in the path of any document which is inserted in the machine.

Recounting now the circuit arrangement of 75

Figure 14, it will be recalled that closing the contact fingers 93 as by the insertion of the document in the machine will function to energize the driving motor 75, as a consequence of which, shaft 35 will be rotated through the medium of belt 78 and pulley 76 so as to move cam 82 in a counterclockwise direction from the position shown in Figure 7. Since the node 84 in the normal or rest position of the machine is directly under the nose 81 of arm 80, the arm in turn will be permitted to drop immediately after the beginning of the driving movement, as a consequence of which, shaft 31 will be rocked in clockwise direction so as to lower the fingers 93 and 94 out of the plane of the document on feed table 17 and the roller 29 will immediately thereafter be caused to engage the upper surface of the document so as to drive it positively through the plane of the 20 mirrors 20 and 21.

It remains to consider the manner in which the circuit to motor 75 is maintained after the contact fingers 93 and 94 have been permitted to return to their normal or open position as a result of the passage of the leading edge of the document thereover. Referring particularly to Figure 6, it will be seen that shaft 35 carries a cam 121, the peripheral surface of which is recessed at 122 throughout a short portion of its arc. The nose 123 of an arm 124 of bell crank 125 rests in the recessed portion 122 of cam 121 when the machine is at rest, a tensile spring 126 acting between the pivotal mounting 127 and the outer extremity of arm 124 assuring proper operation. An angularly disposed arm 128 of bell crank 125 is positioned in the path of a pair of contact fingers generally designated 129 and is operative to close the latter when cam 121 is rotated sufficiently to rock the arm 124 of the bell crank from the position shown in Figure 6 to that position in which its nose rides upon the dwell surface 130 of the cam.

As shown in Figures 6 and 14, the contact element 129 constitutes a pair of spaced normally open contact fingers 131 and 132 which are electrically connected between the conductors 105 and 107. Momentarily, prior to the time when arm 80 operates to drop the contact fingers 93 and 94 to their inoperative and thus open position, the bell crank 125 will be rotated in a clockwise direction to close the contact 129, thus maintaining a closed circuit from the conductor 105 to the conductor 107, thence to conductor 97 and finally to lead wire 92 so that the circuit to the driving motor will not be broken.

Bell crank 125, in addition to its function of maintaining the circuit to the driving motor after disablement of the contacts 93 and 94, is operative to break the circuit to the driving motor at the conclusion of a predetermined movement of the machine. More particularly, the length of the dwell surface 130 will predetermine the time during which arm 128 of bell crank 125 will be maintained in circuit closing position and when cam 130 is rotated to the point where arm 124 may again drop into the recessed portion 122 the contacts 129 will be opened, as shown in Figure 6, thereby breaking the circuit between conductor 105 and the lead-in wire 92, as shown in Figure 14. It will likewise be apparent that the position of the cam 82 is such that when the circuit to the driving motor is broken through the medium of bell crank 125, the arm 80 will have risen 75 to a point adjacent the extremity of node 84 so

as to reposition the contacts 93 and 94 in the path of the next document to be fed while the roller 29 will have been elevated to inoperative position.

In operation the camera is loaded with a length of sensitized material such as film and the documents to be photographed are successively placed upon the feed table 17 and advanced into contact with the upstanding contact fingers 93 and 94, a lateral edge of the document preferably being engaged with a vertical element 151 of the hood 150 to secure complete alignment. If the fingers of the contacts 93 and 94 are caused to engage one another, the circuit to the driving motor 75 is completed as a result of which shaft 35 is rotated, the contact fingers are dropped out of the path of the document and the feed roller 29 dropped into engagement therewith so as to feed the latter through the plane of the mirrors. After passing the plane of the mirrors, the leading edge of the document is engaged by the rollers 40 and 42 and transit of the document is completed by these latter rollers which likewise function to drop the photographed instrument into the hopper 18. Simultaneously with the beginning of the transit of the document through the machine under the feed rollers 25 and 29, the lamps 108 and 109 will be energized by the closing of the circuit established by contacts 93 and 94 and the film in the camera 19 will be fed, simultaneously with the movement of the document through the medium of the shaft 73 and its driving connection 74 and 37 with the shaft 35.

This application is related to the subject matter of the application of Joseph V. Weckbaugh entitled "Method of photographically copying checks, documents, etc.", Serial No. 139,113, filed April 27, 1937. In the Weckbaugh application referred to, as well as in the present invention, the documents to be photographed are moved in a fixed plane between angularly related coplanar reflecting surfaces in synchronism with the movement of a strip of sensitized material such as for example a film or strip of sensitized paper. The document to be photographed is passed from a first to a second set of closely spaced feed rollers positioned on opposite sides of the common plane of the reflecting members and the synchronously moving sensitized material lies in a plane normally disposed to the plane of said reflecting members with the surface of the film normal to the plane of the surface of the document. Preferably the median line of the film is common to the plane of the surface of the document with the result that side-by-side images of the face and reverse surfaces of the document are formed on the sensitized material.

It will be apparent that this method of photography, as well as the means employed to effect the method involved, result in great economy of film for the reason that images of both surfaces of a document may be formed in no greater length of film than was formerly necessary in the recording of only one face of the document.

Furthermore, side-by-side relationship of the images of the front and reverse faces of the document preclude the possibility of confusing related images. Thus, for example, the endorsements appearing on the reverse face of a check will invariably lie alongside of rather than above or below the image of the face of a check.

We claim as our invention:

1. In photographic recording apparatus of the character described, the combination of a document supporting table, a feed roller journaled

- adjacent the plane of said table with its peripheral surface in the plane thereof, a second feed roller journalled on an axis movable toward and away from said first mentioned roller to cause 5 said second mentioned roller to engage said first mentioned roller, a driving motor, a source of electrical energy in circuit relation with said motor, a movable, normally open switch in the plane of said table and in circuit relation between said 10 source of energy and said motor, a second normally open switch in circuit relation between said source of energy and said motor, a driving connection between said motor and said first mentioned roller, means automatically actuated as an 15 incident to closing of said first switch and energizing of said motor to cause said second mentioned roller to move into contacting relationship with said first mentioned roller, means to automatically close said second switch to maintain a 20 circuit to said motor after said first switch has returned to open position, and means to automatically open said second switch after a predetermined movement of said first mentioned feed roller.
- 25 2. In photographic recording apparatus of the character described, the combination of a document supporting table, a feed roller journalled adjacent the plane of said table with its peripheral surface in the plane thereof, a second feed roller journalled on an axis movable toward and away from said first mentioned roller to cause 30 said second mentioned roller to engage said first mentioned roller, a driving motor, a source of electrical energy in circuit relation with said motor, a driving connection between said motor and said first mentioned roller, means automatically actuated as an incident to energizing said motor to cause said second mentioned roller to move 35 into contacting relationship with said first mentioned roller, and means to automatically break the circuit to said motor after a predetermined extent of operation and to move said second mentioned roller out of engagement with said first 40 mentioned roller.
- 45 3. In photographic recording apparatus of the character described, the combination of a document supporting table, a feed roller journalled adjacent the plane of said table with its peripheral surface in the plane thereof, a second feed roller journalled on an axis movable toward and away from said first mentioned roller to cause 50 said second mentioned roller to engage first mentioned roller, a driving motor, a source of electrical energy in circuit relation with said motor, a movable, normally open switch in the plane of said table and in circuit relation between said source of energy and said motor, a driving connection between said motor and said first mentioned roller and means automatically actuated as an incident to energizing said motor to move 55 said switch out of the plane of said table and to cause said second mentioned roller to move into contacting relationship with said first mentioned roller.
- 60 4. In photographic recording apparatus of the character described, the combination of a document supporting table, a feed roller journalled adjacent the plane of said table with its peripheral surface in the plane thereof, a second feed roller journalled on an axis movable toward and away from said first mentioned roller to cause 65 said second mentioned roller to engage said first mentioned roller, a driving motor, a source of electrical energy in circuit relation with said motor, a movable, normally open switch in the plane of said table and in circuit relation between said source of energy and said motor, a driving connection between said motor and said first mentioned roller and means automatically actuated as an incident to energizing said motor to move 70 said switch out of the plane of said table and to cause said second mentioned roller to move into contacting relationship with said first mentioned roller.
- 75 5. In photographic recording apparatus of the character described, the combination of a document supporting table, a feed roller journalled adjacent the plane of said table with its peripheral surface in the plane thereof, a second feed roller journalled on an axis movable toward and away from said first mentioned roller to cause 80 said second mentioned roller to engage said first mentioned roller, a driving motor, a source of electrical energy in circuit relation with said motor, a movable, normally open switch in the plane of said table and in circuit relation between said source of energy and said motor, a driving connection between said motor and said first mentioned roller and means automatically actuated as an incident to energizing said motor to move 85 said switch out of the plane of said table and to cause said second mentioned roller to move into contacting relationship with said first mentioned roller.

- tioned roller, means automatically actuated as an incident to energizing said motor to move said switch out of the plane of said table and to cause said second mentioned roller to move into contacting relationship with said first mentioned roller, and means to break said circuit, move said second mentioned roller out of engagement with said first mentioned roller and return said switch to the plane of said table.
- 10 8. In photographic apparatus of the character described, the combination of a document supporting table, feed rollers journaled adjacent the plane of said table with their peripheral surfaces in the plane thereof, a driving motor, a 15 source of electrical energy in circuit relation

with said motor, a normally open switch in the plane of said table and in circuit relation with said motor, a mechanically actuated, normally open switch in circuit relation with said motor and arranged to be closed to establish a circuit to said motor as an incident to closure of said first mentioned switch, a third normally open switch in circuit relation between said source of electrical energy and said motor, and means actuated by said motor to close said last mentioned switch to maintain a circuit to the motor after restoration of said first mentioned switches to open circuit relation.
